US00D542262S

(12) **United States Design Patent** (10) Patent No.: **US D542,262 S**
(45) Date of Patent: **** May 8, 2007**

(54) **IC RECORDER**

(75) Inventor: **Hiroki Oka**, Tokyo (JP)

(73) Assignee: **Sony Corporation**, Tokyo (JP)

(**) Term: **14 Years**

(21) Appl. No.: **29/234,835**

(22) Filed: **Jul. 25, 2005**

(30) **Foreign Application Priority Data**

Apr. 28, 2005 (JP) D2005-012789

(51) LOC (8) Cl. **14-01**

(52) U.S. Cl. **D14/167**

(58) **Field of Classification Search** D14/167,
D14/154, 168, 188, 496, 156, 160, 161, 162,
D14/163, 164, 165, 192; D16/208; D26/38;
455/351, 350
